AUXILIARY PRINTING ATTACHMENT FOR
PRINTING PRESSESHarvey H. Predmore, Portland, Oreg., assignor
to Albert Edward Pearsall, Vancouver, British
Columbia, Canada

Application March 15, 1939, Serial No. 261,999

5 Claims. (Cl. 101—173)

This invention relates to improvements in two-revolution flat bed printing presses, and has particular reference to an attachment for this type of flat bed presses, whereby printing in at least three colors can be done on said presses at each cycle of operation of the press, and the several colors may be brought into registry for process printing.

Not only is there an insistent demand for color printing, particularly in advertising, but there is a pressing need for a simple, relatively inexpensive device for process printing, which is that method of blending primary colors by printing one or more colors upon another to produce hues of varying tints and shades. Heretofore the use of two-revolution flat bed printing presses for multiple color work has entailed the necessity of printing a run of one color, and subsequently putting the printed sheets through the press a second and third time for successive impressions of different colors. Between each run it has been necessary, of course, to change the color of ink in the fountains and to either replace the inking rollers or thoroughly cleanse them of the ink of the last preceding run. The major difficulty of doing multiple color work on two-revolution flat bed presses, however, is in obtaining an accurate registration of the paper during successive runs through the press.

The present invention contemplates the use of two or more plate cylinders which are so constructed and arranged that they may be moved into printing engagement with the impression cylinder, coincidentally with the movement of the impression cylinder into printing engagement with the reciprocating bed, whereby a sheet to be printed is passed between the impression cylinder and the form on the bed, and between the impression cylinder and the forms on the plate cylinders, during each initial revolution of the impression cylinder. Electrotype, stereotype, or rubber plates may be secured to the plate cylinders in registry with the forms on the reciprocating bed, either as a means of printing three distinct colors, or of making color combinations, as in process work.

Reference is made to Letters Patent No. 2,088-808, issued August 3, 1937, to Albert Edward Pearsall for Two-revolution cylinder printing press, disclosing and describing the combination with a two-revolution flat bed press of a pair of form cylinders, movable into and out of printing engagement with the impression cylinder in timed relation with the movement of the impression cylinder toward and away from the reciprocating

bed. The present invention relates to an improved form of auxiliary printing attachment, such as disclosed in the patent referred to, having new and improved mechanism for mounting the plate cylinders, and for withholding one or both of the plate cylinders from printing contact with the impression cylinder.

It is accordingly an object of the present invention to provide an auxiliary printing attachment for a two-revolution flat bed press for obtaining three or more impressions at each cycle of operation of the press.

It is a further object of the invention to provide a multi-color attachment for a two-revolution flat bed press for printing three or more colors at each cycle of operation of the press.

It is a further object of the invention to provide an attachment for printing presses of the character described, whereby the registration of the several impressions is assured on all printing done, and whereby great economy of equipment and time is obtained.

It is a further object of the invention to provide an auxiliary printing attachment for two-revolution flat bed presses, having a means for withholding one or more of the plate cylinders from printing contact with the impression cylinder.

To the accomplishment of the recited objects and others coordinate therewith, the preferred embodiment of the invention resides in the construction and arrangement of parts hereinafter described, illustrated in the accompanying drawings, and embraced within the scope of the appended claims.

In the drawings:

Figure 1 is a side elevation of an auxiliary printing attachment embodying the present invention as applied to a two-revolution flat bed press.

Figure 2 is a plan view of the device illustrated in Figure 1.

Figure 3 is a sectional elevation taken on the line 3—3 of Figure 2, illustrating the construction of the cam actuated mechanism for moving the plate cylinders out of printing engagement with the impression cylinder.

Figure 4 is a sectional elevation taken on the line 4—4 of Figure 1, illustrating the construction of the arms upon which are mounted the bearings for the plate cylinders.

Figure 5 is a perspective view of a fragmentary portion of the mechanism for holding the plate cylinders out of printing contact with the impression cylinder.

The drawings illustrate a portion of a two-revolution flat bed press provided with side frame members 1 and 2, respectively, which carry the reciprocating bed 3 and the feed board 4. The impression cylinder 5 is carried by the shaft 6, which is journaled at opposite ends in eccentrics 7. Each of the eccentrics 7 is provided with an arm 8 which is connected through a connecting rod 9 to a crank 10 secured upon a shaft 11. Upon being rocked in a downward direction the cranks 10 rock the eccentrics 7 and move the impression cylinder 5, which has picked up a sheet of paper, in a downward direction to bring the paper into printing engagement with the form, not shown, upon the bed 3. After impression and during the second revolution of the impression cylinder, the cranks 10 are raised and the cylinder moved out of contact with the bed. Keyed to the shaft 6 is a gear 12, by means of which the impression cylinder is driven from the main drive of the press, not shown.

The parts thus far named are usual parts in the standard two-revolution flat bed press, and the operation described is regularly carried out in presses of this type and is, therefore, deemed to require no further description.

The auxiliary printing attachment which is the subject matter of the present invention is illustrated as comprising frame members 13-13 which are bolted to the press frame by bolts 14. Each of the frame members 13 is made with parallel wall sections 15 in which is journaled a shaft 16, upon which arms 17 and 18 are pivotally mounted. Adjacent the end of each arm is a split bearing 19 in which is journaled the shafts 20-20 for the plate cylinders 21-21. Thus the plate cylinders are mounted for rotary movement about the shaft 16, each cylinder being capable of movement thereabout independently of the movement of the other cylinder. Each of the plate cylinders occupies a position closely adjacent to and parallel with the impression cylinder 5 and is movable into and out of printing engagement with the impression cylinder by mechanism presently to be described. The shafts 20 are fitted with drive gears 22, each of which meshes with a gear 23 keyed onto the shaft 6, by means of which the plate cylinders are driven at the same peripheral speed as is the impression cylinder 5.

The shaft 6 for the impression cylinder is fitted with gears 24 which mesh with gears 25-25 which turn on stub shafts 26-26. Bolted to each of the gears 25 are cams 27-27, and the gears 25 are hereinafter referred to as cam gears. Engaging the surface of the uppermost cam 27 is a cam follower 28 rotatably mounted upon an arm 29 which serves, under influence of the cam 27, to move a lever arm 30. The lever arm 30 and the arm 29 are made integral with a sleeve 31 fitted over a shaft 32 so that the arms 29 and 30 are permitted a rotary movement about said shaft 32. The free end of the arm 30 is interiorly threaded to receive a bolt 33 designed to bear against a surface 34 on the bearing 19. The lowest cam 27 is engaged by a cam follower 35 rotatably mounted upon an arm 36 which in turn is keyed to the shaft 32 from which projects a lever arm 38. Movement of the lever arm 38 is caused by rotation of the cam 27 by reason of the fact that the lever arm 38 and the arm 36 are rigidly connected to the shaft 32. Threaded through the free end of the lever arm 38 is a bolt 39 designed to bear against a surface 40 on the bearing 19.

Supposing the plate cylinders 21-21 to be nor-

mally urged into printing engagement with the impression cylinder 5, rotation of the cams 27-27 alternately moves the plate cylinders out of printing engagement with the impression cylinder as the surface of the larger diameter of the cam 5 causes the cam followers 28 and 35, respectively, to move the conjoined cam follower arms and lever arms in a direction away from the impression cylinder, which movement serves to rotate the arms 17 and 18 about the shaft 16 to move the plate cylinders 21-21 out of printing engagement with the impression cylinder 5.

The plate cylinders 21 are urged into printing engagement with the impression cylinder 5 by means of spring loaded rods 41-41. The rods 41 are pivotally secured to the respective outer ends of the bearing arms 17 and 18 which support the shafts 20 for the plate cylinders, the other end of each rod projecting through an upstanding portion 42 of the frame of the press. Each rod 41 is equipped with a stop nut 43 adjustably disposed intermediate between the frame member 42 and the bearing arm for the plate cylinder; and disposed between the stop nut 43 and the frame member 42 is a compression spring 44, one end 20 of which bears against the stop nut and the other end against the frame member 42. The compression exerted by the spring 44 is governed by the position of the stop nut 43, the latter 25 threaded onto the end of the rod 41 which projects through the frame member 42 is a nut 45 for limiting the distance which the spring 44 may move the respective plate cylinder 21 toward the impression cylinder. It will be evident that by reason of the mechanism hereinabove described, each of the plate cylinders 21 is mounted for independent movement toward and away from the impression cylinder 5, and that the mechanism for moving each plate cylinder toward and away from the impression cylinder is actuated independently of the actuation of the mechanism for so moving the other plate cylinder.

Applicant has provided a means for withholding either one or both of the plate cylinders from printing engagement with the impression cylinder during operation of the press. It will be appreciated that this may be accomplished in a number of different ways, one of which might take the form of mechanism for selectively disengaging either one or both of the cam gears 25 from the gear 24 at the moment the surface of the larger diameter of the cam is in engagement with the cam follower. In the illustrated embodiment of the invention, however, the desired result is accomplished by means of narrow plates 46-46 slidably fixed upon the frame of the press in position to slide between the frame and the nut 45 threaded onto the end of the rod 41 for limiting the action of the spring 44. Each of the plates 46 carries an upstanding leg or wall portion 47 which, upon movement of the plate 46, may be moved into a position between the nut 45 and the upstanding portion 42 of the frame for arresting return movement of the rod 41 when the respective cam follower (28-35) shall be in engagement with the surface of the smaller diameter of the cam. The wall portion 47 of the plate 46 holds the respective plate cylinder out of printing engagement with the impression cylinder by a distance equal to the thickness of the said wall portion 47.

The plates 46 are moved into inoperative position by means of a strap 48 to which the plates 46 are attached by means of links 49-49. The

strap 48 is moved in one direction by means of a foot treadle 50, which direction of movement causes the plates 46 to be moved into operative position, and is moved in the other direction by means of a spring 51, one end of which is secured to the strap 48 and the other end of which is secured to the frame of the press. Normally, therefore, by reason of the spring 51, the plates 46 are held in inoperative position.

One of the upstanding legs or wall portions 47 on one plate 46 may be of greater length than the upstanding wall portion 47 on the other plate 46, by reason of which a limited movement of the strap 48 will arrest the return movement of but one of the rods 41 and thus cause but one of the plate cylinders 21 to be held out of printing engagement with the impression cylinder. By means of a locking mechanism, not shown, the foot treadle 50 may be selectively locked in either intermediate or full stroke position for withholding either one or both of the plate cylinders from printing engagement with the impression cylinder. Figure 5 illustrates the manner in which the upstanding wall portion 47 of the plate 46 is moved into operative position between the nut 45 and the upstanding portion 42 of the frame to arrest return movement of the rod 41 whenever the strap 48 is moved in the direction indicated by the arrow.

The auxiliary printing attachment illustrated in the drawings includes form rollers 52—52 for which bearings are carried in brackets 37, bolted to the arms 17 and 18. In the construction illustrated two form rollers are provided for each of the plate cylinders, and for each set of form rollers there is provided a vibrator roller 53, the form rollers being equally spaced therefrom by the respective plate cylinders 21. The form rollers 52 are driven by gears 54 fitted to the end of each of the plate cylinders 21, which gears 54 mesh with gears 55 keyed to the shafts of the form rollers.

Each of the drive gears 22 is fitted on its inner side with a cam 56 which engages and rocks an arm 57 mounted on a suitable supporting member, this arm being forked at its forward end to engage a grooved collar 58 secured to the shaft 59 of the vibrator roller 53. A spring 60 is interposed on each shaft 59 between the frame member 37 and the adjacent end of the vibrator roller 53 for the purpose of urging the vibrator roller axially in one direction, whereas the cam 56 serves through the arm 57 to move said roller in the opposite direction.

Suitably supported between the frame members 1 and 2 are inking fountain assemblies, one for each plate cylinder. Each fountain assembly consists of a fountain 61 of the usual type, provided with a fountain roller 62. A ratchet wheel 63 is secured to each fountain roller 62 and is driven by the ratchet 64 provided on the rocker 65 which is actuated by movement of the link 66. The link 66 engages a pin 67 which is offset on a vertical shaft 68. The shaft 68 is rotated in alternately changing directions in an oscillating manner by means of a link 69 secured at one end to a pin 70 offset on the shaft 68 and secured at its other end to a bell crank 71 pivoted at 72 and carrying on its free end a cam follower 73. The cam follower 73 engages the lower cam 27, rotation of which serves to rock the bell crank 71, which in turn oscillates the shaft 68 to actuate the ratchet 64. Thus it will be seen that the ratchet is actuated once upon each revolution of the cam 27, by means of which the fountain roller 62 is

freshly supplied with ink from the fountain 61. The cam follower 73 is held in operative engagement with the cam 27 by means of a spring 74 secured at one end to the end of the bell crank 71, and at its other end to the press frame.

The ductor roller 75, as in the usual arrangement, is designed to transfer the ink from the fountain roller 62 to the vibrator roller 53. The ductor roller 75 is mounted in bearings carried upon a lever arm 76 which is intermittently actuated by a link 77 secured to the bearing arms 17 and 18, respectively, and operated by the movement thereof. The lever arms 76 are pivoted at 78, and the length of the link 77 is adjustable in the well known manner illustrated in the drawings to determine the limits of movement of the lever 76.

In operation, forms for the first color are secured to the bed 3 of the press; forms for the second color are secured in proper registration on one of the plate cylinders 21; and forms for the third color, if three-color printing is to be done, are secured to the other plate cylinder 21. When the forms are in registration, and the ink fountains supplied with ink of the desired colors, the press is set in motion and is fed with sheets of paper in the usual way. Each sheet, on being gripped and carried around upon the surface of the impression cylinder 5, is first brought into impression upon the forms on the bed 3, and then passes into impression on the forms attached to each of the lower and upper plate cylinders in the order named. As the reciprocating bed 3 is about to begin its return movement, the eccentrics 7 are rotated to raise the impression cylinder off impression, and in timed relation with this movement the cams 27 are rotated to bring the cam followers 28 and 35 into engagement with the surface of the larger diameters of the cams, thus moving the plate cylinders 21 away from the impression cylinder 5, and moving the ductor rollers 75 out of contact with the form rollers 52 and into contact with the fountain rollers 62. Due to the fact that the cam gears 25 are rotated at one-half the peripheral speed of the impression cylinders 5, so that the cams 27 are rotated only once during each two revolutions of the impression cylinder, the cam followers 28 and 35 are caused to engage the surface of the larger diameter of the cams during the second revolution of the impression cylinder, whereby the plate cylinders are held out of contact with the impression cylinder and the ductor roller receives a fresh supply of ink from the fountain roller 62.

Having now described my invention and in what manner the same may be used, what I claim as new and desire to protect by Letters Patent is:

1. An auxiliary printing attachment for two-revolution flat bed printing presses having means for moving the impression cylinder of the press toward and away from the reciprocating bed of the press, said device comprising frame members, two pair of arms pivotally mounted on said frame members, a plate cylinder journaled in bearings carried by each said pair of arms, a spring actuated rod secured to each of said arms for urging the plate cylinders into printing engagement with the impression cylinder, a pair of cams adapted to be rotated by rotation of the impression cylinder, a lever arm bearing upon each of the plate cylinder carrying arms and adapted to be moved in opposition to the normal movement of said rod by rotation of said cams for moving said plate cylinders out of printing engagement with said impression cylinder in 75

- timed relation to the movement of the impression cylinder away from the reciprocating bed, and means for arresting the return movement of said rods for holding said plate cylinders out of printing engagement with the impression cylinder.
2. An auxiliary printing attachment for two-revolution flat bed printing presses having means for moving the impression cylinder of the press toward and away from the reciprocating bed of the press, said device comprising frame members, two pair of arms pivotally mounted on said frame members, a plate cylinder journaled in bearing carried by each said pair of arms, resilient means for urging each plate cylinder into printing engagement with the impression cylinder, means for moving said plate cylinders out of printing engagement with said impression cylinder in timed relation to the movement of the impression cylinder away from the reciprocating bed, and means for selectively holding one or more of said plate cylinders out of printing engagement with the impression cylinder.
3. An auxiliary printing attachment for two-revolution flat bed printing presses having means for moving the impression cylinder of the press toward and away from the reciprocating bed of the press, said device comprising a pair of plate cylinders adapted to imprint a sheet carried by the impression cylinder, means for moving each plate cylinder into and out of printing engagement with the impression cylinder in timed relation to the movement of the impression cylinder toward and away from the reciprocating bed, and means for selectively holding one or more of said plate cylinders out of printing engagement with the impression cylinder.
4. An auxiliary printing attachment for a two-revolution flat bed printing press having an impression cylinder mounted for movement toward and away from a reciprocating bed as the bed is reciprocated, a pair of plate cylinders adapted to imprint a sheet carried by the impression cylinder, independently actuated means associated with each said plate cylinder for separately moving each of the plate cylinders into and out of printing engagement with the impression cylinder in timed relation with the movement of the impression cylinder toward and away from the reciprocating bed, means for selectively withholding one or more of said plate cylinders from printing engagement with the impression cylinder, and means associated with each plate cylinder for applying ink thereto.
5. An auxiliary printing attachment for a two-revolution flat bed printing press having an impression cylinder mounted for movement toward and away from the reciprocating bed of the press as the bed is reciprocated, a pair of plate cylinders adapted to imprint a sheet carried by the impression cylinder, means for urging the plate cylinders into printing engagement with the impression cylinder, means adapted to be actuated in timed relation to the movement of the impression cylinder away from the reciprocating bed for moving said plate cylinders out of printing engagement with the impression cylinder, and stop means for arresting the movement of the first named means and selectively operable for withholding one or more of said plate cylinders out of printing engagement with the impression cylinder.

HARVEY H. PREDMORE.
